UNITED STATES PATENT OFFICE.

LODEWYK J. R. HOLST, OF BROOKLYN, NEW YORK, ASSIGNOR OF TWO-
THIRDS TO LOUIS BORSUM, OF PLAINFIELD, NEW JERSEY.

PHOTOGRAPHIC CAMERA.

SPECIFICATION forming part of Letters Patent No. 715,803, dated December 16, 1902.

Application filed June 6, 1901. Serial No. 63,396. (No model.)

To all whom it may concern:

Be it known that I, LODEWYK JAN RUTGER HOLST, a subject of the Queen of the Netherlands, (but having declared my intention of becoming a citizen of the United States and having taken out my first naturalization papers,) residing in the borough of Brooklyn, city of New York, State of New York, have invented certain new and useful Improvements in Photographic Cameras, of which the following is a specification.

This invention relates to cameras provided with focal-plane shutters, and particularly to such cameras employing a mirror-finder hinged in front of the shutter, as shown, for instance, in Letters Patent of the United States, No. 589,349, granted to me August 31, 1897.

The invention consists in certain features of construction associated with the curtain or focal-plane shutter, as is hereinafter described in detail and claimed.

In the accompanying drawings, Figure 1 is a longitudinal vertical section through the rear end of the camera-box; Fig. 2, a transverse section on the line 2 2 of Fig. 1; Fig. 3, a horizontal section showing the upper curtain-roll, partly in plan and partly in horizontal section; Fig. 4, a transverse section on the line 4 4 of Fig. 1; Fig. 5, a front or face view, and Fig. 6 a longitudinal section showing a vane or fan to be applied to one of the roll-shafts to retard the motion of the shutter or curtain and prolong the time of the exposure. Fig. 7 is a plan view showing a metal blank adapted to be bent or folded into shape to constitute a clip that may be applied to the finger-button of one of the roll-shafts and that is adapted to clamp a card or a vane, as shown in Fig. 6, to retard the speed of the shutter. Figs. 8 and 9 are respectively side and end elevations of the clip.

At the back of the camera-box is formed the ordinary rear chamber 1, having doors 2 and 3 and containing the ordinary removable back 4 for holding the plate-holder. The front wall of this chamber is, as usual, formed by a partition 5, having the exposure-opening therein. Mounted adjacent the front face of this partition and respectively at its upper and lower sides are the curtain-rollers 6 7, of which the former is usually and preferably

the spring-drum to be equipped with the ordinary thumb-piece 7' for winding it.

8 is the shutter or curtain, composed of two sections X and Y, wound, respectively, on the upper and lower rolls. To provide for adjustment of the width of the slit between the two sections of the curtain, I have devised the following construction: In the adjacent edges 60 of the curtain-sections are secured by hemming, pasting, or otherwise flat metal strips 9 and 9'. Applied over the edges of the curtain-sections and embracing these strips, so as to be moved longitudinally thereon, are sliding clamps 10 and 10', which may be formed of sheet metal. To the clamp 10 on section X is attached a cord 11, which passes through an aperture at 11' in one end of the strip 9 and is then connected at 11' to the adjacent 70 end of the strip 9' in the edge of the curtain-section Y. The similar sliding clamp 10' is in like manner connected to the strip 9 of the curtain-section X at the opposite side of the curtain. By adjusting these clamps the width 75 of the slit or opening in the shutter may be varied.

I have found by experience that it is desirable to support the edges of the curtain or shutter to keep it smooth and prevent it from 80 fluttering when in action. This I accomplish in the following manner: On the front face of the partition 5, at its sides, (or to the side walls of the camera-box,) I attach shutter-guides 12, whose front faces adjacent the 85 shutter or curtain are curved in a vertical plane, and against these curved faces the curtain travels and is supported. The curved faces of the guides or supports 12 are of considerable radius, and the radius depends in 90 a measure upon the height of the camera-box or the distance between the two rolls. It is apparent that at times the curtain is wound mostly upon the lower roll, thereby increasing its diameter, and at other times mostly 95 upon the upper roll, thereby increasing its diameter, and that when the shutter is tripped and the curtain is being unwound from the upper roll and wound upon the lower roll it will be traveling in planes constantly varying in angular relation to a vertical plane, and yet at all times its edges will be supported and guided by contact with the curved faces of the guides 12. It is desirable that

the width of the front or guiding faces of the guides 12 should be as great as possible, particularly at their central parts, in order that the sides of the curtain may overlap them to a sufficient extent to prevent the passage of light to the rear around the edges of the curtain. By beveling their inner edges 13 to prevent reduction in the cross-sectional area of the light-cone at its point of contact with the plate—or, in other words, to prevent the guides 12 from reducing the effective area of the exposure-opening in the partition 5—I am enabled to make the curved faces of the guides of correspondingly-greater width. I prefer also, as shown at 13', that they shall be widest at the center and decrease in width toward the ends.

In order that the curtain may with facility be wound upon the upper roll and without having its spindle and thumb-wheel project objectionally from the side of the box, I have devised the following construction: Within the roll, which may be hollow or having cavity 14, Fig. 2, formed in one end, I secure a disk 15, with a square or angular aperture therein. An operating-spindle 16, shaped at its inner end portion to fit the aperture, slides therein, so that it may be drawn out for convenient manipulation, its outward movement being limited by a cross-pin 18, abutting against the inner face of the cup-shaped disk 19, secured in the side of the camera-box.

In front of the curtain I have shown the usual front-light guards, consisting of a transverse portion 24, attached to the bottom of the camera, extending between its side walls and up in front of the lower roll. From the sides thereof rise vertical side-light guards 25 of appropriate width and attached, respectively, to the opposite walls of the camera-box. Owing to the variation in diameter of the upper roll, as the curtain is wound or unwound thereon these side-light guards, which are usually made of sheet metal, cannot be so disposed at their upper ends as to effectively prevent the passage of light-rays at all times. I therefore provide at their upper ends flexible strips or extensions 26, which may be made of any suitable fabric—as velvet, plush, leather, &c.—and which at all times, irrespective of variation of diameter of the upper roll, bear upon it and effectively exclude the light at all times. So far as I am aware, this is a new feature in cameras of this general class and constitutes an important and effective improvement thereon.

In the drawings, A represents the side supports for the hinged mirror-frame, (not shown,) and C the transverse support, which parts also act as light-guards.

D is the lever for raising the mirror-frame and also actuating the latch E to trip the shutter.

As shown at 27, Fig. 3, the button on the winding-spindle of the upper roll may be notched or slit transversely. By means of this simple expedient I may apply or attach to the

button an ordinary card of suitable dimensions or a flat thin piece of celluloid or hard rubber, which when the shutter is tripped acts as a vane or fan to equalize and retard its speed. By using fans of different area I may thus within considerable limits control or regulate the period of exposure. In Figs. 6 and 7 I have shown a vane or fan consisting of two slotted sections 28 29, clamped together by a set-screw 30, the area of the fan being thus adjustable. Such a device may be inserted in the notch 27, being retained therein frictionally or otherwise. In Figs. 9 and 10 I have shown a clip adapted to clamp upon the button and having closely adjacent or spring jaws 31 to hold the fan (shown in Fig. 6) or any card or suitable piece of flat material. The clip is preferably made of sheet metal and bent up from the blank shown in Fig. 8.

I claim as my invention—

1. In a focal-plane-shutter photographic camera, the combination of the curtain-rolls, the curtain and the curved curtain-edge guides.

2. In a focal-plane-shutter photographic camera, the combination of the curtain-rolls, the curtain and the curved curtain-edge guides having their inner edges beveled rearwardly and outwardly.

3. In a focal-plane-shutter photographic camera, the combination of the curtain-rolls, the curtain and the curved curtain-edge guides of greater width at the center than at the ends and having their inner edges beveled rearwardly and outwardly.

4. In a focal-plane-shutter photographic camera, the combination of the curtain-sections having stiffening-bars in the edges, a friction-clip embracing each edge and sliding thereon, and a cord extending from each clip to the corner of its curtain-section and thence to the corresponding corner of the other curtain-section.

5. In a focal-plane-shutter photographic camera, the combination with the curtain and its rolls, of the bottom and side light-guards, and flexible extensions from the upper ends of the side guards bearing on the periphery of the upper roll adjacent its ends.

6. In a focal-plane-shutter photographic camera, the combination with the curtain, of the spring-roll, the winding-rolls, the endwise-movable spindle of one of the rolls, and a vane removably attached to the endwise-movable spindle to retard the speed.

7. In a focal-plane-shutter photographic camera, the combination of the curtain, its spring-roll, its winding-roll having a telescoping winding-spindle, and a speed-controlling vane applied to the spindle.

In testimony whereof I have hereunto subscribed my name.

L. J. R. HOLST.
